UNITED STATES PATENT OFFICE.

CHARLES A. CREAPO, OF ST. PAUL, MINNESOTA.

LADDER.

1,155,995.

Specification of Letters Patent.

Patented Oct. 5, 1915.

Application filed November 6, 1913. Serial No. 799,415.

To all whom it may concern:

Be it known that I, CHARLES A. CREAPO, a citizen of the United States, residing at St. Paul, in the county of Ramsey and State of Minnesota, have invented a new and useful Improvement in Ladders, of which the following is a specification.

The primary object of my invention is the production of a step ladder, which is particularly adapted for use in connection with sleeping car berths, whereby a passenger may easily mount an upper berth with safety, and be provided with means easily accessible for quickly climbing down from the berth on to the floor of the aisle.

To these ends my invention consists of a ladder which can be easily hung when not in use from the curtain rail of the berth out of the way, and when desired lowered into position for use from the berth.

The invention also provides a ladder which can be folded into a small compact package for storage, and when opened forms a durable rigid ladder, which will not accidentally collapse. The ladder is also constructed so that when turned up and hung from the curtain rail it acts as a guard preventing a passenger from falling out of an upper berth on to the floor of the aisle.

In the accompanying drawing forming part of this specification, Figure 1 is a side elevation of my invention applied in use to a sleeping car, the broken line position indicating the ladder when it is hung from the curtain rail. Fig. 2 is an enlarged detail of the ladder partly in section; Fig. 3 is a side elevation of the ladder when in folded condition, and Fig. 4 is an enlarged detail in section of one of the interlocking joints employed between the sections of the rails.

In the drawing A and B indicate the rails of the ladder and C the steps. The rails are similar in construction, each consisting of a series of jointed sections 2, which are secured together by headed pins 3 fastened to an end of one member and passing loosely through a slot 4 in the end of the adjacent member. This slot and pin connection allows a limited longitudinal movement between the sections constituting each rail. The sections of the rails are positioned opposite each other in pairs, every alternate pair being provided with a step C secured rigidly thereto. The pairs of sections to which said steps are attached are placed with their ends overlapping the inner sides of the ends of the ad-

jacent pairs of sections, all of the sections being so hinged together as to fold into the position indicated in Fig. 3 and form a compact package for storage purposes.

Each of the opposite ends of the outer sections of the rails is provided with a hook 5, the body of which is secured on the inner face of the section by screws 6 or other suitable means, said body having a slot 7 corresponding with the slot 4 through the section and the pin 3 passing through both of said slots.

The inner section of the rail adjacent the outer section on which the hook 5 is rigidly secured is provided with a bolt 8 forming a lug over which the hook 5 engages when the sections are in fully extended position and in readiness for use. This hook and lug form an interlocking connection holding the rails in rigid longitudinal position when the sections are extended for use.

The upper sections of the rails are provided with links 9 freely secured by pivots to the ends of the sections and provided with hooks 11 having enlarged headed ends 12 which are adapted to engage through slotted plates 13 mounted on the edge 14 of the frame of the upper berth 15 of a sleeping car. The slotted plates are fastened to the edge 14 such as by screws 16 and the enlarged headed ends 12 of the hooks 11 are adapted to be passed into engagement with said plates through enlarged openings 17. The lower ends of the rails are also provided with links 18 pivotally secured at 19 to the lower ends of the sections of said rails, said links being rigidly secured together by a lower step 20 and provided with hooks 21, which are adapted to rest on the floor of the aisle when the ladder is adjusted for use to the upper berth and with the sections of the rails in fully extended and interlocked condition. While in this condition the ladder can be used for mounting the upper berth or for descending from the berth into the aisle, the weight of the person placed upon the steps of the ladder serving to hold the hooks 5 in interlocked condition.

When desired the ladder may be raised by its lower end and the hooks 21 engaged over the curtain rail 22 of the berth as indicated by broken lines in Fig. 1. The raising of the lower end of the ladder longitudinally serves to automatically release the hooks 5 out of engagement with their respective in-

terlocking lugs and free the sections. When desired the ladder can be raised by a person in the upper berth by the use of a cord 23 secured to the lowermost step 20 and passing over the successive steps across the alternate edges thereof as illustrated through screw eyes 24. By pulling upon the upper free end of the cord the ladder is folded upwardly from its lower end, the interlocking joints being opened automatically. After the ladder has been raised sufficiently the lower end may be engaged by its hooks 21 over the curtain rail and the ladder left hanging while the hooks 11 remain engaged with the edge 14 of the berth. While hanging in this position the ladder acts as a guard to prevent a passenger from falling out of the upper berth.

In accordance with the patent statutes I have described the principles of operation of my invention together with the apparatus which I now consider to represent the best embodiment thereof, but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. A ladder, comprising, in combination, a plurality of foldable sections having steps, the sides of said sections constituting the side rails of the ladder and being hinged together to fold lengthwise of the ladder, the connection between each pair of said sides consisting of a slot in one member and a pin on the other member passing through said slot, permitting said sections to turn or move outwardly longitudinally and a rigid hook carried by one of said members and the other of said members having a lug with which said hook engages to hold said member rigid when the latter are in outermost position and which disengages when said members are moved backwardly.

2. A ladder, comprising, in combination,

a plurality of foldable sections arranged end to end and forming side rails and having steps between said side rails and connected with pairs of said sections, interlocking connections between the sides of said sections of each rail adapted to uphold said sections rigidly in longitudinal position, means for detachably securing the uppermost of said sections to a support, and hooks on the lowermost of said sections adapted to support the lower end of the ladder in raised position on an object when the ladder is not in use.

3. A ladder, comprising, in combination, a plurality of foldable sections having steps, the sides of said sections constituting the side rails of the ladder, interlocking connections between the sides of said sections adapted to uphold said sections rigidly in longitudinal position when the ladder is in raised position, and to unlock when said sections are moved longitudinally apart, means for detachably securing the upper end of the ladder to an object and a flexible element secured to the lowermost section of the ladder and passing in a zig zag course over the successive steps toward the upper end of the ladder, whereby the sections of the ladder are adapted to be unlocked and folded together from the lower end toward the upper end by pulling upwardly upon the free end of said flexible element.

4. In combination with the floor of an upper sleeping car berth and the curtain rail of said berth, of a ladder composed of foldable sections having means for detachably engaging its upper end to the floor of said berth and means for detachably securing its lower end in raised position on said rail to act as a guard at the side of said berth.

In testimony whereof, I have signed my name to this specification, in the presence of two subscribing witnesses.

CHARLES A. CREAPO.
